Harold D. Penney ATTORNEY

UNITED STATES PATENT OFFICE.

EDWARD O. TINSLEY, OF NEW YORK, N. Y., ASSIGNOR TO ROBERT GAIR COMPANY, OF NEW YORK, N. Y., A CORPORATION OF NEW YORK.

VENDING DISPLAY SUPPORT.

Application filed October 2, 1925. Serial No. 60,060.

My present invention relates to an improved vending display support preferably made of box board and the like, which may be printed to accentuate and advertise the article which is to be displayed thereon, and which will hold the article to be vended in an inclined manner.

One of the objects of my invention is to make such a device out of one piece of material with no loose ends, all of the component portions being connected one to the other, and which when in collapsed position is foldable entirely flat and may be erected by a simple motion.

Another object of my invention is to provide in a construction of the class described that the article supporting portion or ledge thereof not only will rigidly and perfectly support a heavy article, but will also act as a tie across the folded scored planes of the display support in order to act as a keel to prevent accidental collapse.

In the preferred form of construction the display support in its erected form is a four sided angular frame, two of the major surfaces thereof being scored from the apex of an angle to the base of the angle, the article supporting and tie element of the display support being folded or scored to the bottom major surface of the display support so that when the supporting and tie element is folded in operative position, its score or fold lines are in opposition, relative to the folding angle, to the bottom major surface upon which it is developed.

Referring to the accompanying drawing Fig. 1 is a perspective view of the display support in erect position and showing the ledge and tie member in engagement with the display face of the support and an article supported for display on the ledge.

Fig. 2 is a side elevation of the display support in erect position, the ledge and tie member being disengaged from the display face and in extended position relative thereto.

Fig. 3 is an end elevation of Fig. 2, viewed in direction of the arrow.

Fig. 4 is a view of the blank for forming the display support, and

Fig. 5 is a view showing the display support in collapsed flat folded condition.

Similar reference characters denote similar parts throughout the several views.

Referring to Figs. 2 and 4, the display

support has a bottom 10, defined by fold lines forming an equilateral triangle, the bottom 10 serving to support the display support on a plane surface. The sides 11 and 12 are substantially right angle triangles foldably connected along their longer sides to the side fold lines of the bottom 10, the sides 11 and 12, when the display support is in erect position as in Fig. 1, converging towards each other and being joined together at their convergence at the apex of the bottom 10 in a line disposed vertically to the apex of the bottom 10 by the attaching extension or flap 13 foldably connected to the side 11. The display face generally denoted by 14, Fig. 1, in shape is an isosceles triangle consisting of two triangular portions 15 and 16, foldably connected along one of their sides to the hypotenuses of the sides 11 and 12 and secured together on their other sides to form the display face by the attaching extension or flap 17 on the portion 15, Figs. 3 and 4. The sides 11 and 12 when joined together at their point of convergence connect the bottom 10 and the display face 14 at the apexes of the bottom and the display face. The triangular portions 15 and 16 are provided near their bases with the transverse cuts or slits 18 and 19. The display face 14, Fig. 1, has the fold line 20 extending from its apex to the mid point of its base, the fold line 20 being provided by the fold line of the attaching flap 17 when the portions 15 and 16 are joined together to form the display face. The ledge and tie member generally denoted by 21, Fig. 1, consists of the support 22 and the ledge and tie 23. The support 22 is foldably connected along one of its sides to the base of the bottom 10, Figs. 1 and 4, and the ledge and tie 23 is foldably connected along one of its sides to the support 22, the ledge and tie 23 being provided on its opposite side with the locking tabs 24 and 25 which are engageable in the cuts 18 and 19 when the support is in erect condition. The bottom 10 is provided with the fold line 26, Figs. 1 and 4, extending from its apex to the mid point of its base and which is extended across the support 22 as 27, and further extended across the ledge and tie 23, as 28, the fold lines 27 and 28 dividing the ledge and tie 23 and the support 22 respectively into two equal portions.

The blank, Fig. 4, includes the mid portion 10 constituting the bottom section, of

equilateral triangular shape, defined on two of its sides by the scorings 29 and 30 and on its base by the scoring 31, and having foldably connected thereto by the scorings 29 and 30 the wing portions 32 and 33 and having foldably connected thereto by the scoring 31 the oblong portion 34, and having the before mentioned scoring 26 extending from the apex of the bottom to the mid point of its base. The wing portions 32 and 33 include the triangular side sections 11 and 12 and the triangular display face sections 15 and 16, the side section 11 being defined from the display face section 15 by the diagonal scoring 34 and the side section 12 being defined from the display face section 16 by the diagonal scoring 35, the side section 11 having on its base the attaching flap section 13 defined therefrom by the scoring 36 and the display face section having on one of its sides the attaching flap section 17 defined therefrom by the scoring 20 before mentioned as extending from the apex of the display face 14 to the mid point of its base when the display support is in erect condition. The display face sections 15 and 16 have therein the transverse cuts 18 and 19 near their bases at one side of the sections. The oblong portion 34 includes the support 22 and the ledge and tie 23, defined from each other by the scoring 37 and respectively divided into two equal portions by the scorings 27 and 28 in extension of the scoring 26, the ledge and tie 23 having on its free side the locking tabs 24 and 25.

To erect the display support from the blank, the side sections 11 and 12 are folded upwardly on their foldable connections to the bottom section 10 and are so secured together at their converging ends by the attaching flap 17; the display face sections 15 and 16 are folded downwardly and inwardly on their foldable connections to the side sections 11 and 12 and brought over the face section 10 and secured together by the attaching flap 17, the display face 14 thus formed lying over the bottom section 10 at an upward and rearward inclination; the support section 22 is folded upwardly on its foldable connection to the bottom section 10, and the ledge and tie section 23 is folded downwardly on its foldable connection to the support section 22 and the locking tabs 24 and 25 are engaged in the cuts 18 and 19 of the display face.

To collapse the display support for convenience in shipping and storing, the locking tabs 24 and 25 are disengaged from the cuts 18 and 19, and the sides of the display support are brought together or compressed so that the display face 14 is extended forwardly by bending on its fold line 20 and the bottom 10 is extended rearwardly by bending on its fold line 26 and the respective equal portions of the support 22 and

ledge and tie 23 are brought together by bending on the fold lines 27 and 28, so that the display support assumes the flat collapsed form shown in Fig. 5.

What I claim and desire to protect by Letters Patent is:

1. In a display support formed by folding a blank, in combination, a triangular back for superposing the display support on a plane surface, triangular side walls each foldably connected along one of their sides to the back and supported thereby, an upwardly extending and rearwardly inclined triangular display face foldably connected along two of its sides to the sides of the side walls opposite to their sides of connection to the back and supported by the side walls, the display face being free at its base, a supporting member foldably connected along one of its sides to the base of the back, and a ledge foldably connected along one of its sides to the opposite side of said supporting member and detachably engageable on its other side to the display face near the base of said face for supporting an article on the ledge at the inclination of and bearing against the display face.

2. In a display support formed by folding a blank, in combination, a triangular back for superposing the display support on a plane surface, triangular side walls each foldably connected along one of their sides to the back and supported thereby, an upwardly and rearwardly inclined triangular display face foldably connected along two of its sides to the sides of the side walls opposite to their sides of connection to the back and supported by the side walls, the display face being free at its base, a supporting member foldably connected along one of its sides to the base of the back, a ledge foldably connected along one of its sides to the opposite side of said supporting member and detachably engageable on its other side with the display face near the base of said face for supporting an article on the ledge at the inclination of and bearing against the display face, and means for foldably collapsing the display support when in erect display condition and folding the display support in flat collapsed form.

3. In a display support formed by folding a blank, in combination, a triangular back for superposing the display support on a plane surface, triangular side walls each foldably connected along one of their sides to the back and supported thereby and converging towards the apex of the back, an upwardly and rearwardly inclined triangular display face foldably connected along two of its sides to the sides of the side walls opposite to their sides of connection to the back and supported by the side walls over the back and having its apex in line with the apex of the back, the display face being

- free at its base, the side walls being secured together at their point of convergence and providing means for connecting the apexes of the back and display face, a supporting member foldably connected along one of its sides to the base of the back, and a ledge foldably connected along one of its sides to the opposite side of said supporting member and detachably engageable on its other side with the display face near the base of said face for supporting an article on the ledge at the inclination of and bearing against the display face. 70
4. In a display support formed by folding a blank, in combination, a triangular back for superposing the display support on a plane surface, triangular side walls each foldably connected along one of their sides to the back and supported thereby and converging towards the apex of the back, an upwardly extending and rearwardly inclined triangular display face foldably connected along two of its sides to the sides of the side walls opposite to their sides of connection to the back and supported by the side walls over the back and having its apex in line with the apex of the back, the display face being free at its base, the side walls being secured together at their point of convergence and providing means for connecting the apexes of the back and display face, a supporting member foldably connected along one of its sides to the base of the back, and a ledge foldably connected along one of its sides to the opposite side of said supporting member and detachably engageable on its other side to the display face near the base of said face for supporting an article on the ledge at the inclination of and bearing against the display face, a fold line extending from the apex of the back to the mid line of the base of the back, a fold line extending from the apex of the display face to the mid line of the base of said face, a fold line extending transversely of the supporting member in the mid line of said member and in extension of the fold line of the back, and a fold line extending transversely of the ledge in the mid line of the ledge and in extension of the fold line of the supporting member. 80
5. A blank for forming a display support by folding the blank on scorings of the blank, said blank consisting of a triangular mid portion defined on the blank by scorings and constituting a bottom section, wing portions connected to the triangular mid portion along the scoring at the sides of the mid portion and converging at one of their ends towards each other, and an oblong portion connected to the mid portion along the scoring at the base of the mid portion, said wing portions each including a triangular side section and a triangular display face section defined from each other by a diagonal scoring, one of said wing portions having on one of its ends means for securing the side sections together and having means on one of its sides for securing the display face section defined from each other by a diagonal scoring, one of said wing portions having on one of its ends means for securing the side sections together and having means on one of its sides for securing the display face sections together, said oblong portion including a support section and a ledge and tie section defined therefrom by a scoring, the ledge and tie section being provided with means engageable with means appurtenant to the display face sections for detachably securing the ledge and tie section to the display face sections when said sections are secured together. 85
6. A blank for forming a display support by folding the blank on scorings of the blank, said blank consisting of a triangular mid portion defined on the blank by scorings and constituting a bottom section, said mid portion having a scoring extending from the apex of the triangle to the mid point of the base, wing portions connected to the triangular mid portion along the scoring at the sides of the mid portion and converging at one of their ends towards each other, and an oblong portion connected to the mid portion along the scoring at the base of the mid portion and having a scoring extending across the oblong portion in the line of extension of said apex to base scoring of the mid portion, said wing portions each including a triangular side section and a triangular display face section defined from each other by a diagonal scoring, one of said wing portions having on one of its ends means for securing the side sections together and having means on one of its sides and defined by a scoring extending longitudinally of the wing portion for securing the display face sections together, the last mentioned scoring constituting a scoring extending from the apex to the mid point of the base of the display face when the display face sections are secured together, said oblong portion including a support section and a ledge and tie section defined therefrom by a scoring, the ledge and tie section being provided with means engageable with means appurtenant to the display face sections for detachably securing the ledge and tie section to the display face sections when said sections are secured together. 90
7. In a display support formed by folding, in combination, a base member having a broad flat surface superimposable on a plane surface for support thereby, walls each connected at the edge of one of its sides to a side of said flat surface, the side faces of said walls extending in a plane transversely to the plane of said flat surface, the edges of the sides of said walls opposite to the edges thereof connected to said flat surface lying in a plane at an inclination to the plane of said flat surface, and a display face having 100
- 110
- 115
- 120
- 125
- 130

a flat surface connected at sides thereof to the last mentioned edges of said walls and lying in the inclined plane of the last mentioned edges.

8. In a display support formed by folding, in combination, a base member having a flat surface triangular in outline and superimposable on a plane surface for support thereby, triangular walls each connected at the bottom edge of one of its sides to a side of said flat surface, the side faces of said walls extending upwardly at an angle to the plane of said flat surface, the top edges of said walls lying in a plane at an inclination to the plane of said flat surface, and a display face having a flat surface connected at sides thereof to the top edges of said walls and lying in the inclined plane of said top edges.
10. 9. In a display support formed by folding in combination, a base member having a flat surface superimposable on a plane surface for support thereby, walls each connected at the edge of one of its sides to a side of said flat surface, the side faces of said walls extending in a plane transversely to the plane of said flat surface, the edges of the sides of said walls opposite to the edges thereof connected to said flat surface lying in a plane at an inclination to the plane of said flat surface, a display face having a flat surface connected at sides thereof to the last mentioned edges of said walls and lying in the inclined plane of the last mentioned edges, and means connected to an end of the first mentioned flat surface and foldably disposable on said display face transversely thereof for supporting an article on said means at the inclination of said display face.
12. 10. In a display support formed by folding, in combination, a base member having a flat surface triangular in outline and superimposable on a plane surface for support thereby, triangular walls each connected at the bottom edge of one of its sides to a side of said flat surface, the side faces of said walls extending upwardly at an angle to the plane of said flat surface, the top edges of said walls lying in a plane at an inclination to the plane of said flat surface, a display face having a flat surface connected at sides thereof to the top edges of said walls in the inclined plane of said top edges, and means connected to the end of the first mentioned flat surface and foldably disposable on said display face transversely thereof and interlockably engageable therewith for providing a ledge for supporting an article thereon in the inclined plane of said display face.

to the plane of said flat surface, a display face having a flat surface connected at sides thereof to the top edges of said walls and lying in the inclined plane of said top edges, and means connected to the end of the first mentioned flat surface and foldably disposable for providing a ledge extending transversely of said display face for supporting an article on said ledge at the inclination of said display face.

11. In a display support formed by folding, in combination, a base member having a flat surface triangular in outline, right angle triangular walls each connected at the bottom edge of its shorter side to a side of said flat surface, the side faces of said walls extending upwardly at right angles to the plane of said flat surface, the top edges of the hypotenuses of said walls lying in a plane at an inclination to the plane of said flat surface, and a display face having a flat surface connected at side edges thereof to the top edges of said walls in the inclined plane of said top edges.

12. In a display support formed by folding in combination, a base member having a flat surface triangular in outline, right angle triangular walls each connected at the bottom edge of its shorter side to a side of said flat surface, the side faces of said walls extending upwardly at right angles to the plane of said flat surface, the top edges of the hypotenuses of said walls lying in a plane at an inclination to the plane of said flat surface, a display face having a flat surface connected at sides edges thereof to the top edges of said walls in the inclined plane of said top edges, and means connected to the end of the first mentioned flat surface and foldably disposable on said display face transversely thereof and interlockably engageable therewith for providing a ledge for supporting an article thereon in the inclined plane of said display face.

Signed at New York, in the county of New York and State of New York, this 21st day of September, A. D. 1925.

EDWARD O. TINSLEY.
